(57) **CLAIM**

The ornamental design for a sewer hose weight, as shown and described.

DESCRIPTION

FIG. 1 is a top, front, left side perspective view of a sewer hose weight showing our new design;

FIG. 2 is a bottom, rear, right side perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof; and,

FIG. 8 is a right side elevational view thereof.

The broken lines illustrate portions of the sewer hose weight that form no part of the claimed design.

1 Claim, 8 Drawing Sheets
